UNITED STATES PATENT OFFICE.

HAROLD V. McCORMICK, OF LONG BEACH, NEW YORK, ASSIGNOR, BY MESNE ASSIGNMENTS, TO SHUR LOC ELEVATOR SAFETY CORPORATION, OF NEWARK, NEW JERSEY, A CORPORATION OF NEW JERSEY.

ELEVATOR.

Application filed January 29, 1927. Serial No. 164,415.

This invention is particularly concerned with devices whereby the opening of any shaft door is prevented unless the elevator car is positioned with respect to the door and for preventing the starting of the car from such position when the shaft door is not fully closed.

One particular object of the invention is to provide improved means whereby the shaft door is locked against effective opening movement unless the car is properly positioned with reference thereto. Another particular object is to provide means whereby a switch in the motor control connections shall be opened when the shaft door receives effective opening movement, the switch remaining open while the door is open or partially open so that the car cannot be moved while the door is open or partially open, notwithstanding accidental or inadvertent movement of the car controller handle. Still another object is to prevent the possible opening of the shaft door as the car passes through the corresponding position without stopping, the door releasing devices being ineffective while power is supplied to the motor which moves the car. Other features of the invention will be referred to herein-after in connection with the description of that embodiment of the invention which has been chosen for illustration herein. In the drawings, in which that embodiment of the invention is illustrated—

Figure 1 is a view partly in elevation and partly diagrammatic, showing so much of the complete elevator system, including the car, the electrical connections through which is controlled the operation of the electric motor by which the movement of the car is effected or controlled, the car controller and its electrical connections, and a part of the devices through which the operation of the safety switch is effected or controlled, as is necessary to enable the invention to be understood, the shaft door being also indicated.

Figure 2 is a view in elevation, as seen from the left hand in Figure 1 and on a larger scale, of the devices through which the operation of the safety switch is effected or controlled.

Figures 3, 4 and 5 are detail views, mainly in elevation, of the devices directly in opera-

tive relation with the shaft door, such devices being shown in part but on a smaller scale in Figure 2.

Figure 6 is a detail view in elevation illustrating a modification of a portion of the switch operating devices.

In the drawings a portion of one of the shaft doors which guard the openings at the several floors into the shaftway, is indicated at *a*, such door being movable, as usual, to open or close the opening into the shaftway. It is shown as carrying a roller bearing *a'* stud *a'* adapted to engage, in the last of the closing movement of the door, a forked lever *b* which is pivotally mounted on a bracket *b'* fixed on the sill of the shaft opening. The bracket is conveniently supplied with a stop *b*² to limit the movement of the forked lever in one direction and may also be conveniently provided with a stop tooth or detent *b*³ for a purpose to be explained.

Pivotally mounted on the forked lever *b* is a bell crank, the longer arm *c* of which forms a dog for cooperation under certain conditions with the stop tooth or detent *b*³ above mentioned. The shorter arm *c'* of the bell crank has pivotally connected thereto a link *d* which at its other end is pivotally connected to one arm *e* of a bell crank, which is also mounted on the floor or sill of the shaft opening. The other arm *e'* of this bell crank engages an arm *f* of a third bell crank pivoted on a bracket *f'* on the floor or sill, the other and substantially vertical arm *f*² carrying a roller *f*³ which is adapted to be projected by the effective opening movement of the door *a* toward the car, which is sufficiently indicated at *g*, or toward a cooperating part carried by the car, as will be described. Means, such as a spring *f*⁴, tend normally to press the arm *f*² and its roller *f*³ toward the car.

Normally the door *a* is locked against effective opening movement through the engagement of the dog *c*, on the forked lever *b*, with the detent *b*³, although the parts are so formed and proportioned that the door may have a slight movement, perhaps to the extent of an inch or so, in the opening direction. The construction and arrangement of the parts is such that the offering of resistance to the movement of the bell crank *f*, *f*² is necessary to disengage the dog *c* from

the detent b^2 so as to permit the forked lever b to swing from its initial position, shown in Figure 3, to or toward its final position, indicated in Figure 5, in which position the door is free for effective movement. Such resistance is offered only when the car is positioned with reference to the door to be opened and the means by which such resistance is offered is preferably carried by the car itself. Furthermore, the character of the resistance means is such that when it has served its purpose in unlocking the shaft door and the further movement of the projected member f^3 , it will itself be moved by the further movement of such projected member and will, by such movement, effect the opening of a switch in the motor control circuit which will prevent movement of the car while the door is open or partially open. The devices involved in these operations will now be described.

As already stated, the dog c , which engages the stop b^3 to prevent effective movement of the forked lever b and therefore opening movement of the door, is one member of a bell crank, the other member c' of which is connected by a link d with the bell crank e by which the projecting movement of the member f^3 is effected. The bell crank c, c' is held normally in its locking position, as shown in Figure 3, by the preponderance of weight of the dog or bell crank member c and if no resistance is offered to the movement of the projected member f^3 in the initial and ineffective opening movement of the shaft door and the corresponding movement of the forked lever b , the bell crank c, c' will not be rocked on its pivot and the dog c will not be disengaged from the stop tooth b^3 , so that the movement of the forked lever and the movement of the shaft door will be limited to a small extent, the door not being released for effective opening movement. If, however, resistance to the movement of the projected member f^3 is offered, then the bell crank c, c' will be rocked on its axis, the dog member c will be disengaged from the stop tooth b^3 , the extent of its movement being limited by a shoulder formed on the lever b^4 , and the lever b and the shaft door a will be released for effective opening movement. In such movement the forked lever b will be swung from the position shown in Figure 3 to the position shown in Figure 5, whereby the roller a' is released from the forked lever and the door is permitted to have its full opening movement. The further movement of the member f^3 , in the continued movement of the forked lever b , is taken advantage of, as already mentioned, to effect the opening of the switch in the motor control circuit, so that the car cannot be moved.

In the embodiment of the invention illustrated, the device which offers the resistance

to the movement of the projected member f^3 necessary to effect the unlocking of the door and also acts in the continued movement of the forked lever b and the projected member f^3 to effect the opening of the switch, is a shoe h of suitable length and suitably formed, as indicated in Figure 2, which is movably supported on the car g . As shown, the shoe h is carried by an arm or slide h' supported for movement in a horizontal direction in suitable guides h^2 . A toggle lever i is pivotally mounted, as at i' , on a fixed part of the car and is connected at one end, as at i^2 , with a sliding bar k mounted for movement in guides h^3 on the arm or slide h' which carries the shoe h . At the other end an extension i^3 of the toggle is connected by a link i^4 with one member of a bell crank i^5 , supported by brackets g' on the car. The other member of the bell crank i^5 is connected by a link i^6 with one member of a bell crank i^7 , also supported on the car. The horizontal member of the bell crank i^7 is preferably weighted, as at i^8 , so that it tends normally, through the connections already described, to hold the toggle i with its members in line, with the bar k and the shoe h in their forward or lefthand positions, the shoe being then in the position to offer the required resistance to the initial movement of the roller or projected member f^3 , to effect the unlocking of the shaft door. The movement of the toggle in flattening is transmitted to the shoe h through bar k , pivot k' between the bar and crank k^2 , short arm of crank k^2 , pivot k^3 (mounting the crank upon the slide h'), and the slide h' to shoe h . Pivotal movement of crank k^2 is resisted by linkage o, o' and o^2 , thus causing the slide to move outwardly.

As it is undesirable that any shaft door be unlocked when the car is passing through the position of the door, without stopping, provision is made whereby the shoe h is retired from its unlocking position so long as power is supplied to the motor which effects or controls the movement of the car. As shown in Figure 1, there is connected to the weighted arm of the bell crank i^7 the core l of a solenoid l' which, through connections indicated at l^2 , is connected into the armature circuit m' of the motor m , (to the field coils of which current may be supplied through connections at m^2 , from the feed wires m^3 , as shown in Figure 1,) which effects or controls the movement of the car, so that when power is supplied to the motor the solenoid is energized and the weighted arm i^8 of the bell crank i^7 is held against the action of gravity in such position that, as shown in Figure 2, the toggle i is broken and the shoe h is withdrawn from the position in which it would otherwise offer the necessary resistance to the movement of the roller f^3 . When, however, power ceases to

be supplied to the motor through the opening of the circuit in any manner, gravity acts on the weighted arm i^8 to straighten the toggle i and hold the shoe h in its forward position to offer the necessary resistance to the movement of the roller f^3 .

The motor m and the usual control panel, indicated generally at n , not necessary to be described in detail herein, may be constructed and arranged as usual, being located usually in the pent house at the top of the elevator shaft.

Although the shoe h offers, in its forward position, the relatively slight degree of resistance necessary to effect the unlocking of the shaft door, as already described, it is also itself susceptible of movement rearwardly or to the right hand in Figure 2 by the continued projection of the roller f^3 in the continued movement of the forked lever b after it has been released and this movement of the shoe, (which can take place, as will be understood, only when the effective opening movement of the door has commenced) is taken advantage of to open a switch in the control circuit of the elevator motor so that the car cannot be moved after the effective opening movement of the car and door has commenced. To effect this result, the bar k , to which the forward end of the toggle i is pivotally connected, as already described, is engaged through a pin k' with the vertical arm of the bell crank k^2 pivotally mounted, as at k^3 , on the arm or slide h' . The horizontal arm of the bell crank k^2 is connected through a link o with one arm of the bell crank o' , also supported by the brackets g' , the other arm of the bell crank o' being connected through a link o^2 with an arm p of a switch p' , a weighted arm p^2 being applied to the axis of the switch and tending to move the switch from closed to open position.

It will be understood that the controller s is connected to the control panel n in substantially the usual manner, except for the introduction of the interlock switch p' , and that when the contact maker s' is moved to one side or the other it closes the circuit through the terminals s^2, s^3 , or s^4, s^5 , as the case may be, from the feed wires m^3 through the connections r, r' , as the case may be, to one or the other of the relay magnets t^{11}, t^{12} , thereby closing the circuit through the armature coils of the elevator motor m to drive it in one direction or the other as may be required. It will further be understood that the switch p' is interposed in the connections r' so that when the switch p' is shifted from closed to open position the circuit, including the switches controlled by the relay magnets t^{11}, t^{12} will be broken and power will not be supplied to the motor m . Therefore, the car cannot be moved by the motor when the switch p' is open, whether

or not the controller s is in position to start the car. As the switch p' is opened as soon as effective opening movement of a shaft door has commenced, the car cannot be started, despite accidental or unintentional movement of the controller from neutral position to starting position.

It will be understood that in the operation of the devices described, when power is cut off from the motor m it is also cut off from the solenoid or other electro-motive device l' with the result that the weighted member i^8 drops, the link i^4 is moved to the right, the link i^4 is moved upward and the toggle i is flattened. As the weighted member p^2 of the switch p' offers, through the arm p , link o^2 , bell crank o^4 and link o , resistance to the rocking of the bell crank k^2 on its pivot on slide h' , the flattening of the toggle i , acting through the sliding bar k , the pin k' bell crank k^2 , and pivot k^3 on slide h' will cause the slide h' and the shoe h to move forward. Similarly, when the electro-motive device l' is energized, as it will be when power is supplied to the motor m , the toggle i will be broken and the slide h' and shoe h will be withdrawn. When, therefore, the motor m is energized to move the car up or down, the shoe h is withdrawn so that it fails to offer the resistance necessary to the releasing of the door and the door therefore cannot be opened so long as power is supplied to the car. Furthermore, when the car has been stopped and the door has received effective opening movement, the movement of the door, acting through the arm f^2 will thrust the shoe h backward, so that the bell crank k^2 which is pivoted on the slide h' , then finding its fulcrum on the then stationary pin k' , will be rocked, the link o will be moved upward, the link o^2 will be moved to the left and the switch p' will be opened so that power cannot be supplied to the motor to move the car either up or down.

In Figure 6 of the drawings is shown, as a substitute for the solenoid, a stalled motor t , on the shaft of which is a pinion t' in engagement with the segmental rack t^2 . The latter is formed on one arm t^3 of a bell crank, the other arm t^4 of which has connected with it the link t^6 . A stop arm t^5 is formed with the bell crank to limit the motion. It will be understood that the stalled motor t is connected into the circuit of the elevator motor in the same manner as already described with respect to the solenoid l' , so that when power is supplied to the motor m of the elevator the motor t is energized and holds the bell crank t^3, t^4 in position, shown in Figure 6, against the influence of gravity on the weighted arm t^3 of the bell crank, substantially as already described with respect to the arrangement shown in Figure 1, while if the circuit of the main motor m is opened the circuit of the

motor t will also be opened and gravity will act through the weighted arm t^3 to straighten the toggle i in the same manner as already described.

5 It will be understood that various changes in details of construction and arrangement can be made to suit different conditions of use and that, except as pointed out in the accompanying claims, the invention is not 10 restricted to the particular construction and arrangement shown and described herein.

I claim as my invention:

1. In an elevator having a shaft door, a car, a motor to operate the car, a car controller on the car and means to supply power to the motor under the control of the controller, a locking device normally preventing effective opening movement of the door, means in operative relation with the locking device to release the door, means carried by the car for cooperation with said last named means to effect release of the door when the car is positioned with respect to the door, a switch mounted on the car and 20 included in the connections to control the motor, and connections whereby the switch is opened by the movement of the last mentioned means.

2. In an elevator having a shaft door, a car, a motor to operate the car, a car controller on the car and means to supply power to the motor under the control of the controller, a locking device normally preventing effective opening movement of the door, 35 means including a movable member to operate the locking device to release the door in the initial movement of the door when resistance is offered to the movement of said movable member, and means carried by the car to offer the required resistance to the movement of the movable member.

3. In an elevator having a shaft door, a car, a motor to operate the car, a car controller on the car and means to supply power to the motor under the control of the controller, a locking device normally preventing effective opening movement of the door, means including a movable member to operate the locking device to release the door in the initial movement of the door when resistance is offered to the movement of said movable member, yielding means carried by the car to offer the required resistance to the movement of the movable member and to 50 move with the movable member in its continued movement after the unlocking of the car, and devices operated by the continued movement of said yielding means to prevent the movement of the car by the motor.

4. In an elevator having a shaft door, a car, a motor to operate the car, a car controller on the car and means to supply power to the motor under the control of the controller, a locking device normally preventing

effective opening movement of the door, means including a movable member to operate the locking device to release the door in the initial movement of the door when resistance is offered to the movement of said movable member, yielding means carried by the car to offer the required resistance to the movement of the movable member and to move with the movable member in its continued movement after the unlocking of the car, a switch mounted on the car and included in the connections to control the motor, and devices whereby the switch is opened by the continued movement of the said yielding means. 70

5. In an elevator having a shaft door, a car, a motor to operate the car, a car controller on the car and means to supply power to the motor under the control of the controller, a locking device normally preventing effective opening movement of the door, means to operate the locking device to release the door, means carried by the car for cooperation with said last named means to effect release of the locking device when the car is positioned with respect to the door, said last mentioned means being movable out of operative position, and devices interconnected with the motor controlling means to withdraw said movable means from operative position when power is supplied to the motor. 75

6. In an elevator having a shaft door, a car, a motor to operate the car, a car controller on the car and means to supply power to the motor under the control of the controller, a locking device normally preventing effective opening movement of the door, means to operate the locking device to release the door, means carried by the car for cooperation with said last named means to effect release of the locking device when the car is positioned with respect to the door, said last mentioned means being movable out of operative position, and electromechanical devices inter-connected with the motor controlling means to withdraw said movable means from operative position when power is supplied to the motor. 100

110

7. In an elevator having a shaft door, a car, a motor to operate the car, a car controller on the car and means to supply power to the motor under the control of the controller, a locking device normally preventing effective opening movement of the door, means to operate the locking device to release the door, means carried by the car for cooperation with said last named means to effect release of the locking device when the car is positioned with respect to the door, said last mentioned means being movable out of operative position, electromechanical devices inter-connected with the motor controlling means to withdraw said movable means from operative position when power is supplied to the motor, a switch mounted 115

120

125

130

on the car and included in the connections to control the motor, and means in operative relation with said movable means to open the switch and prevent movement of the car 5 when the effective opening movement of the door has commenced.

8. In an elevator having a shaft door, a car, a motor to operate the car, a car controller on the car and means to supply power 10 to the motor under the control of the controller, a locking device normally preventing effective opening movement of the door, means in operative relation with the locking device to release the door, means carried by the car for cooperation with said last 15 named means to effect release of the door when the car is positioned with respect to the door and movable into and out of operative position, and means to effect movement of said last mentioned means and including an electro-motive device to determine the operation of said last mentioned means, said electro-motive device being included in the connections with the car motor to receive power only when the car motor receives 20 power, a switch mounted on the car and included in the connections to control the car motor, and means to operate the switch.

9. In an elevator having a shaft door, a car, a motor to operate the car, a car controller on the car and means to supply power 25 to the motor under the control of the controller, a locking device normally preventing effective opening movement of the door,

means in operative relation with the locking device to release the door, means carried by the car for cooperation with said last 30 named means to effect release of the door when the car is positioned with respect to the door and movable into and out of operative position, and means to effect movement of said last mentioned means and including an electro-motive device to determine the operation of said last mentioned means, said electro-motive device being included in the connections with the car motor to receive power only when the car motor receives 35 power, a switch mounted on the car and included in the connections to control the car motor, and means to operate the switch.

10. In an elevator, the combination of a door, a forked lever mounted on the door 40 sill in position to be engaged by the door, a bracket supporting the lever and a stop tooth, a bell crank mounted on the lever and having one arm formed as a dog to engage a stop on the bracket, a link connected to 45 the other arm of the bell crank, and means to prevent movement of the link in the initial movement of the door and lever to cause the bell crank to be rocked on its axis and the dog to be disengaged from the stop. 50

This specification signed this 27th day of January, A. D. 1927. 55

HAROLD V. McCORMICK.
